CONTINUOUS STRIP MAGAZINE RAZOR.

Gustav B. Jensen, New York, N. Y.

Application April 24, 1947, Serial No. 743,616

2 Claims. (Cl. 30—40)

1

This invention relates to safety razors, and more particularly to continuous strip safety razors of the magazine type wherein a continuous strip blade providing the equivalent of many individual blades is enclosed in a unitary expendable magazine which is readily insertable in and removable from a razor frame. The blade of the razor of the present invention is wound upon supply and take-up spools within the magazine, which encloses the blade completely except for the length thereof in use and provides protection both to the blade and to the user thereof. The magazine is designed to be permanently assembled together upon manufacture with the blade therein, so that when the whole length of the blade in the magazine has been used the magazine is to be discarded.

An object of the present invention is to provide a razor employing a continuous strip blade in which the blade will be substantially enclosed in a magazine removably insertable in the razor, so as to obviate all need for handling of the blade by the user.

Another object of the present invention is to provide a razor in which the cutting member is enclosed within a disposable magazine containing the equivalent of a large number of the common single or double-edged blades.

My invention will be better understood from an examination of the following detailed description taken in conjunction with the accompanying drawings in which:

Fig. 1 is a perspective view of a razor embodying the principles of the present invention;

Fig. 2 is a perspective view of the razor frame with its cover lifted exposing the magazine mounted therein and showing the engagement of the portion of the blade in position for use with a support and guard therefor forming part of the razor frame;

Fig. 3 is a perspective view of the magazine removed from the razor frame;

Fig. 4 shows the interior of the magazine with a strip blade wound upon supply and take-up spools and passing over guides which stretch and position it for engagement with the support and guard of the razor frame;

Fig. 5 is a view of the interior of the razor frame with the magazine removed, exposing the driving mechanism by which the continuous strip blade is advanced;

Fig. 6 is a lengthwise sectional view of the assembled razor, taken along line 6—6 of Fig. 1 but showing the razor in inverted position, as it would be held in use; and

2
Fig. 7 is a cross section of the assembled razor, taken along line 7—7 of Fig. 6, also showing the razor in inverted position.

Referring to Fig. 1, the razor of the present invention when seen from the exterior presents a frame 4 to which is hinged a cover 5. A strip blade shown at 10 in position for use is supported within a guard 6 extending between a pair of jaws 1 extending from and forming part of the frame 4.

The guard 6, shown in cross section in Fig. 6, is formed with a slot 21 just wide enough to accommodate the blade 10 and has a depth of some three-quarters of the width of the blade. The blade 10 fits snugly within the slot 21 and abuts against the bottom thereof. Front and rear lips 22 and 23 on the guard provide for proper exposure of the blade while preventing its contact with the user's skin except in a position nearly parallel thereto.

Referring again to Fig. 1, suitable clasping means are provided to retain the cover 5 closed with the frame 4. The frame 4 and cover 5 are formed with a recess 8 behind the jaws 1, but closure between the frame and cover is complete along the edge of the cover. A razor so constructed may be roughly 3½" x 2" x ½" and is readily grasped in the user's hand.

Fig. 2 shows the interior of the razor frame 4 with the cover 5 thereof opened. A magazine 30 contains the continuous strip blade and substantially fills the interior of the razor frame, except for a space below the magazine occupied by the driving mechanism which advances the blade. The strip blade, which is wound upon supply and take-up spools within the magazine, passes in its progress from one to the other of these spools over a pair of projecting guides 34 formed in the magazine, and in its passage between these guides engages the guard 6. The magazine may be accurately located in the frame 4 by means of bosses projecting from the frame, so that the portion of the blade in use in the guard 6 will be supported by the guard alone, free of stresses imposed by the magazine except for a stretching between the guides 34. A driving wheel 65, which rotates the take-up spool, projects up through an aperture 39 through the magazine, as described below.

Fig. 3 is a perspective view of the magazine 30 removed from the razor. The magazine is formed of upper and lower stampings 31 and 32 joined by conventional means, such as detents. The height between the faces of the stampings 31 and 32 is sufficient to accommodate the blade which is wound on the supply and take-up spools en-

closed between the stampings. The strip blade 10 may be observed stretched across the guides 34 and entering the magazine through a slotted opening 33 from which it passes to the take-up spool. The blade coming from the supply spool emerges from a complementary slotted opening (not shown) on the other side of the magazine in order to pass over the guides.

Two cylindrical apertures 35 and 39 are shown extending through the magazine. These apertures form the centers about which the supply and take-up spools rotate. Flanges 38 extend into these apertures from the upper and lower stampings, so as to provide cylindrical surfaces on which the supply and take-up spools may ride. The supply and take-up spools, numbered 50 and 51 respectively, may be seen between the opposite flanges 38 of the apertures 35 and 39. An annular projection 53 on the take-up spool 51 extends radially inward from the cylindrical surface defined by the flanges 38 which carry the take-up spool. This annular projection 53 is slotted at diametrically opposite points 54 for engagement with the driving wheel of the razor frame which serves to advance the continuous strip blade.

The interior of the magazine is shown in Fig. 4, which is a perspective view of the lower stamping 32 with the supply and take-up spools therein. Lower stamping 32 appears in Fig. 4 as an open-topped box having a bottom 36 and a side wall 37 extending all the way around, but split down to the level of the bottom 36 at the openings 33. At these openings the side 37 is cut back from the bottom 36 and bent inwardly to provide, in conjunction with the guides 34 which likewise consist of curved portions of the side 37, a smooth bearing surface for the blade 10 in its motion from the supply to the take-up spool. When the magazine is first placed into use the entire length of the blade 10, except that necessary to be threaded across the guides 34 of the magazine and around to the take-up spool 51, is coiled on the supply spool 50. As the section of blade stretched in the guard 6 of the razor frame 4 between the guides 34 becomes dulled, a fresh length of the blade is drawn into position between the guides by rotation of the take-up spool. The supply spool and, except for a projection required for driving it, the take-up spool also may be made in the form of simple cylinders. Retaining flanges thereon are unnecessary since the stampings 31 and 32 which form the top and bottom of the magazine prevent movement of the blade axially of the spools. The supply spool 50 thus consists of a simple cylinder frictionally retained on flanges 38 of which the lower flange belonging to the lower stamping 32 is shown in Fig. 4. The supply spool fits snugly on these flanges so as to prevent slackening of the blade between the guides 34 where it engages the guard 6. The blade 10 is sharpened along its edge and is preserved from damaging contact with the upper stamping 31 by suspension in an oil bath.

The driving mechanism which advances the blade to provide a fresh section thereof in the guard is shown in Figs. 5 and 6. Affixed to the inside of the frame 4 shown in Fig. 5 is a gear train which translates the reciprocating motion of a hand-operated plunger 60 into rotary motion of a driving wheel 65. The driving wheel 65 engages the take-up spool 51 by means of keys 66 thereon which mate with the slots 54 in the annular projection of the take-up spool when the magazine is inserted into the razor frame. The

plunger 60 includes two longitudinal members 61 and 62 fitting into guide rails 63 affixed to the inside of the frame. One longitudinal member 62 carries teeth forming a rack 67 which engage a gear 64 journaled in the frame between the longitudinal members. A one-way clutch is provided between the gear 64 and the wheel 65, which is concentric therewith, so that the wheel 65 rotates only when the gear 64 is driven counterclockwise as the plunger 60 is pushed back into the frame after being drawn out. The one-way clutch may consist of a ratchet wheel 70 affixed to a shaft 71 which is journaled in the driving wheel 65. This construction is best seen in Fig. 6. The shaft 71 has a square end 72 which engages a square hole in the gear 64. A pawl 73, mounted in the driving wheel 65, constrains the driving wheel to turn with the ratchet wheel and gear when the latter turns counterclockwise under the influence of the rack 67 and plunger 60.

While I have disclosed my invention by reference to a specific embodiment, it is intended to be illustrative of the principles thereof only. It will be understood that all variations and modifications falling within the true scope of my invention are intended to be included within the scope of the appended claims.

I claim:

1. A blade magazine for a razor employing a continuous strip blade, said magazine comprising upper and lower casings forming a closed flat box having a substantially rectangular shape of greater length than breadth, a pair of jaws extending one from either side of one end of the magazine in a direction generally parallel to the long dimension of the magazine, two circular apertures in each of said casings disposed one behind the other along the long dimension of the magazine, the apertures in one casing being respectively coaxial with the apertures in the other casing, inwardly extending flanges on the said apertures, a supply spool journaled on the flanges of the apertures adjacent the said jaws, a take-up spool journaled on the flanges of the apertures remote from the said jaws, an annular ring on the said take-up spool adapted to provide positive engagement with driving mechanism external to the magazine, slotted apertures in the said jaws, and a continuous strip blade wound upon the supply and take-up spools and led from the supply to the take-up spool outside the magazine through one of the said slotted apertures, between the jaws, and through the other of the said slotted apertures back into the magazine and onto the take-up spool.

2. A continuous strip razor comprising a frame formed of a substantially rectangular flat box with projecting jaws at one end thereof and a slotted blade support and guard extending therebetween to accommodate externally of the box a section of a continuous strip blade, a magazine for the blade formed of a substantially rectangular flat box possessing substantially the same proportions as the razor frame except for the slotted blade support and guard and adapted to fit within the frame, the said magazine accommodating supply and take-up spools therein one behind the other in the sense of the long dimension of the frame, a continuous strip blade coiled on the supply and take-up spools within the magazine and passing from one to the other of the said spools externally of the magazine over the jaws thereof, and means to advance the blade by a known and substantially constant amount including a spool-engaging member affixed to the in-

side of the frame in position to engage the take-up spool upon insertion of the magazine into the frame, a gear affixed to the frame concentrically with the said spool-engaging member, a one-way clutch arranged between the gear and the spool-engaging member and a rack arranged on the frame and engaging the said gear, whereby a single stroke of the rack rotates the take-up spool through a fixed angle and advances the blade by a substantially constant amount.
